UNITED STATES PATENT OFFICE.

ALBERT KRAUTH, OF HAMILTON, OHIO.

MANIFOLDING-MACHINE.

1,142,442.

Specification of Letters Patent.

Patented June 8, 1915.

Application filed May 31, 1913. Serial No. 770,956.

To all whom it may concern:

Be it known that I, ALBERT KRAUTH, a citizen of the United States, residing at Hamilton, in the county of Butler and State 5 of Ohio, have invented certain new and useful Improvements in Manifolding-Machines, of which the following is a specification.

My invention relates to an improvement in autographic registers, and in certain aspects to a mechanical movement for producing an intermittent power transmission constant as to direction of its functioning motion and interval of operation imparted on the power stroke of an oscillating mechanism and released therefrom on its normalizing stroke.

The disclosure herein illustrated and described is applicable to manifolding devices or autographic registers, comprising a preferred embodiment, for feeding invariable constant lengths of paper upon each operative stroke of the crank handle to reduce the manual operation for effecting a delivery of a predetermined length of paper from the machine. The delivered lengths are uniform as to size, which are in the nature of preprinted autographic blanks necessitating accurate feed, so as to insure a full text delivery for each operation and deliver the continuous sheet in registry with a point of severance, so that a length can be severed from the sheet along its divisional line dividing it from the continuous sheet.

The machine is operated by a crank handle which is oscillated within confined limits engaging a positive stop at the end of each stroke, which renders it impossible to operate the paper feeding rolls beyond that required for a predetermined advance of paper, eliminating the use of any releasable stop elements in connection with the handle or otherwise requiring the attention of the operator as now commonly employed in a machine of this character operating under a measured stroke.

With my improvement no releasable stop members are required, and the confined stroke or reciprocating movement of the crank handle can be micrometrically adjusted, so that its power movement can be regulated with accuracy, relative to the prescribed operation required of the feeding mechanism.

An object, therefore, of my invention is 55 to provide means movable within a confined area capable of transmitting motion during one of its strokes and neutral in a second, in

its to and fro movements between the confined area to operate functioning mechanism constant in its direction of motion, 60 with the power means releasable therefrom during its neutral stroke for producing a constant invariable functioning operation beyond the manual manipulation of the operator.

Another object of my invention is to provide crank mechanism movable between definitely located limiting stops, capable of being engaged with a driven member during one stroke to transmit motion thereto, releasing in its second stroke for converting a differential movement into a constant direction of movement.

Another object of my invention is to provide a pair of coacting paper-feeding rolls 75 in geared connection with each other positively rotated in one direction by reciprocating crank handle movable within confined limits, having a rack element adapted to be engaged with the gear of one of the 80 rolls during one stroke of the crank handle and released therefrom during the second stroke, and further, to provide means for delicately or micrometrically adjusting or regulating the confining limits relative to a 85 prescribed interval of operation required for rotating the paper feeding rolls to advance a measured length of paper.

Another object of my invention is to provide a crank handle movable within confined 90 limits with a power-transmitting member movable therewith and radially thereby so as to change the plane of movement of said transmitting member for engaging or disengaging the same during one of its movements with a member or mechanism receiving its motion or power therefrom.

Another object of my invention is to provide an autographic register with means for supporting a web or series of webs within 100 the register comprising a compartment receptacle for individually supporting each web separate from a second and unitarily removable from the register.

The various other features of my invention will be more fully set forth in the description of the accompanying drawings illustrating the preferred embodiment of my invention, in a specific use, that of a manifolding device for autographic registers, but 105 which also may be regarded in the nature of a mechanical movement, and the reference herein to a manifolding device is designated merely for the purpose of more clearly and

conveniently describing the various parts, and a use to aid in a clear understanding of the invention.

Manifolding devices have a variety of uses, with the specific use to which the type of machine herein disclosed is designed is well known in the art in which a general result is adapted to be sought, namely to deliver a constant invariable length of paper within a certain definite movement of a crank handle, and known to the trade as a measured stroke manifolding machine. To meet the requirements of the users of this type of machine it has heretofore been necessary to make a special machine for each user for the reason that no standard length of autographic blank has been adopted. Therefore, great difficulty has been experienced in a type of geared machine utilizing coating paper-feeding rolls, between which the paper is fed, to construct a machine, in which adjustments could be made to render the same applicable to various lengths of autographic blanks. In the gear type of machines it has been experienced that delicate machining had to be resorted to in some instances to produce the proper length of feed of certain sized autographic blanks within a prescribed movement of the crank handle. Further, it has also been customary to provide manually releasable locking means or arresting mechanism to define the movements of the crank lever or manipulating handle, which, under the control of the operator, were apt to be inadvertently actuated, allowing the lever to be moved beyond its predetermined limit.

It has been found that the use of a pair of coating paper-feeding rolls positively rotated by intermeshing gears produce the most satisfactory result for definitely feeding the strip of paper. Therefore such feeding instrumentalities are employed in my present invention, with the mechanism for rotating them comprised in a reciprocating or oscillating crank handle positively movable in one direction and automatically movable in its normalizing direction, with an elimination of any releasing mechanism requiring the attention of the operator. The manual performance to deliver a length of paper is materially lessened over the machines known to the art.

In the accompanying drawings, Figure 1 is a central vertical section through the apparatus. Fig. 2 is a side elevation thereof with a portion thereof illustrated in section. Fig. 3 is a section on line 3-3, Fig. 2. Fig. 4 is a detail side elevation of a modified form of web supporting tray. Fig. 5 is a section on line 5-5, Fig. 4. Fig. 6 is a side elevation similar to Fig. 2, illustrating a modified view of paper feeding roll propelling mechanism.

In the drawings, 1 represents the base of the manifolding device 2, 3, the casing side

walls secured to the base, and 4, 5, the end walls hingedly mounted to the side walls 2, 3, for access to the interior of the casing. The upper portion of the casing is provided with the usual form of writing-table 6, and the margin-frame 7, which may be hingedly mounted to one of the side frames or otherwise. As before stated, the feeding rolls are of well-known construction, comprising a lower roll 8 confined in its bearings and an upper roll 9, journaled so as to be yieldingly movable toward the lower roll, to bring the peripheries of said rolls into frictional engagement with each other, said upper roll being journaled within slide-blocks slidably mounted within slide-ways formed in the side-frames or walls 2, 3.

The upper roll 9 is provided with a gear 10 intermeshing with the gear 11 of the lower roll 8 for positively rotating said gears. The upper roll is adapted to be moved away from its frictional engagement with the lower roll to separate said rolls in loading the machine, which mechanism for accomplishing such result may be of any well known form, as illustrated herein comprises a pair of bell crank levers 12, one pivotally mounted upon the axis of the lower roll at each end thereof, each having an arm adapted to engage with the axis of the upper roll to move the same toward and from the lower roll.

13 represents a rock shaft journaled in the side frames provided with pins adapted to engage with said bell crank lever to rock the same, and 14 represents a handle fixed to the rock shaft, and as illustrated, connected exterior of the machine.

With the rolls in direct geared connection it follows that they must relatively rotate in opposing directions with their surface tangent traversing in the same direction, thereby preventing any reverse rotation or slippage of any one of the rolls upon the paper between them. The roll 8 being journaled in rigid bearings, constitutes the driving rolls of the series with which the propelling or actuating mechanism is connected during an operating period, so that it cannot be displaced or its positive feeding direction interfered with. Upon one end of its axis a gear 15 is fixed, in this instance, exterior of the side wall or frame 2, adapted to intermesh a toothed contour of the actuating or propelling mechanism and during one stroke thereof. The propelling or actuating mechanism in its preferred embodiment comprises the following instrumentalities:—16 represents a crank handle adjacent the side frame 3, fixed upon the crank shaft 17, journaled in the side frames 2, 3, beyond which the shaft projects. 18 represents a crank arm projecting from the crank shaft 17, into a slot 19, formed in the guide member 20. The guide member is loosely

mounted on the crank shaft but oscillates therewith through the functioning qualification of the crank arm. The guide member, as illustrated in Figs. 2 and 3, is of hollow formation, adapted to receive the sector member 21, slideable therein, having its lower edge covering the crank slot 19 and engaged by the nose of the crank arm for moving the sector member 21 outwardly radially from the axis of the crank shaft 17. The sector member 21 has a circular toothed contour serving as a rack to engage with the teeth of the roll gear 15 in one line of its travel and during one oscillating stroke of the crank handle 16 and disengaged from the said gear during a reverse line of travel. The sector member 21 has a slot 22, preferably along a diametrical line, within which a spring 23 is seated, one end of the spring 20 engaged with one wall of the slot and its opposite end with a cross piece 24 rigidly connected to the guide member 20 and projected through the slot 22 for urging the sector member toward the axis of the crank shaft to automatically return the sector member to its normal released position within the guide member. Thus to bring the propelling contour of the sector member into its operative line of travel and traverse coincidentally with the movement of the crank handle it will be seen that the crank arm, in its initial movement, say in a forward direction, will move idly until it has moved from the wall 25, of the crank slot 19, and 35 engaged with the opposite wall 26, with the nose of the crank arm in its arc of movement from one wall toward the other, forcing the sector member outward radially a sufficient distance to change the line of travel of the 40 rack or propelling contour to bring the pitch line of its teeth tangent with the pitch line of the gear 15. The continued stroke of the crank handle in such forward direction, maintaining the parts in their propelling 45 position, transmitting motion to the feed rolls. The release of the sector member from the gear 15 is accomplished by substantially a reverse operation from that just described, but its movement is automatic 50 after a release of the crank handle by the operator through the compressed energy of a spring fixed to the crank shaft. Thus the contour line of travel of the propelling mechanism is changed coördinately with the 55 direction of its oscillating stroke.

To insure the proper positioning of the sector member before its propelling motion is transmitted to the gear 15 in one instance, and released therefrom or its line of travel 60 changed in a second instance, I provide the sector member 21 with catch elements 27, 28, the catch element 27 adapted to be engaged with the latch or pawl 29, while the catch element 28 is adapted to be engaged by the 65 latch or pawl 30. The pawl 29 retains or

holds the sector member against oscillating movement or stroke at one of its traversing limits, while the pawl 30 functions when the sector member is in opposite position. The pawls retain or hold the sector member 70 against any propelling movement until after it has been raised or lowered, so as not to transmit any motion to the feeding roll, which might be detrimental to their paper feeding operation. It will be seen that the 75 pawl 29 will arrest any forward movement of the guide and sector members until after the sector member has been raised or moved radially outward and positioned to its intermeshing line of travel with the gear 15, 80 whereupon the catch 27 will be elevated or moved slightly beyond the hook end of the pawl and released therefrom. This is accomplished during the idle movement of the crank arm in moving from one wall to the 85 other of the crank slot in the guide member. A similar operation, but in a reverse movement, is obtained by the catch 28 and pawl 30 to release the sector member from its engagement with the gear 15 to insure that 90 it has been removed therefrom before the propelling mechanism moves to normal. The shaft 17 is provided with a spring 31, one end thereof fixed to the shaft while the opposite end of the spring is fixed to a rigid 95 support, or, as illustrated, to the side frame, for automatically restoring the crank handle and its oscillating members to normal. The operator, in a feeding operation, being merely required to move the crank handle 100 in one direction, after which the parts will normalize automatically, reducing the manual performance to a minimum.

To confine the oscillating movement of the crank handle within a definite limit, I 105 provide stop lugs 32, 33, rigid with the side frame, each having a screw 34 connected therewith, adapted to engage the guide member 20 at each end of its oscillating stroke, the screws providing a micrometer 110 adjustment to limit the oscillation or strokes with precision relative to the revolution required to advance or feed a predetermined measured length of paper.

In Fig. 6, I have shown a modified form 115 of construction of the guide and sector members, but which change is merely structural, the operation remaining the same as that described for the form of construction shown in Figs. 2 and 3. In this latter instance, the guide member 20 is provided with the ears 34', 34', one pair upon each end thereof, the ears being orificed to receive the stems 35, 35, respectively, projecting from the sector member 21. Each stem 125 has a spring 36 encircling the same, one end thereof engaged with the stem and the opposite end with one of the ears for yieldingly urging the sector member 21 toward the axis of the crank shaft. 130

It is obvious that various modified forms of construction can be readily devised for accomplishing the result herein disclosed comprehensive within the scope of this invention, and I, therefore, do not wish to be limited to the specific forms of construction, except wherein specific mention thereof is made in the claims.

In manifolding machines of this type or paper feeding devices, it has been customary to support the webs of paper between journals fixed to the side frame or frames, or components of the side frames, which, in some instances, made it very inconvenient to insert or remove the webs from their journals, it being inconvenient to gain access to the webs and their supporting mechanism, unless they were exteriorly accessible, which necessitated an open or skeleton style of side frame or the journals provided with hand holds projecting exterior of the frame.

In the disclosure herein, I provide a web supporting tray 37 bodily removable from the interior of the casing of the apparatus, which tray is provided in compartments 38, each receiving a web, as illustrated in Fig. 1, relying upon the weight of the web or weighted core insert to produce the proper tension required in unwinding the web. In such instance, the tension is differential, decreasing as the web is being unwound, offering advantage in using some grades of paper. Such removable web support or tray, besides offering advantage for properly supporting the webs within the machine, enables the use of a sealed casing, preventing unauthorized persons from gaining access to the webs.

In the form shown in Figs. 4 and 5, I have provided the removable tray with yielding arms 37', angularly projected from two of the walls of the tray, with each arm provided with a cupped disk engaging into the core of the web of paper. This form of web support is substantially the same as that shown in my prior Patent, No. 925,851, and shown herein merely for the purpose of illustrating a varied range of use of a removable web supporting tray.

Having described my invention, I claim:

1. A device of the nature disclosed combining a pair of coacting paper feeding rolls, gears for rotatively connecting the rolls, a gear segment diametrically movable into and out of intermesh with one of said roll gears, engaging therewith in an advancing movement of the gear segment and disengaged therefrom in its normalizing movement.

2. A device of the nature disclosed combining a pair of coacting paper feeding rolls, gears for rotatively connecting the rolls, a swinging toothed member movable radially from its axis for changing its ra-

dius travel for alternate engagement and disengagement with one of the gears of said rolls for operating the feed roll for a definite paper advance.

3. A device of the nature disclosed combining rotative coacting paper feeding elements, and an oscillating member movable radially from its axis to operatively connect with said paper feeding elements in an advancing stroke and releasable therefrom in a normalizing stroke for successively feeding invariable constant lengths of paper.

4. A device of the nature disclosed combining a swinging power transmitting member adapted to be reciprocated radially from its axis in different planes in its advancing and normalizing movement, and a member capable of being engaged with said power transmitting element and rotated thereby in an advancing plane of movement of said transmitting member.

5. A device of the nature disclosed combining a member adapted to be oscillated, a power transmitting member having a circumferential contour and movable radially upon said first member to alter its radii planes, said members oscillating unitarily, and a member located relatively to the contour of said power transmitting member to be engaged therewith in one stroke for functioning said last-named member.

6. A device of the nature disclosed combining a pair of coacting paper feeding rolls, and an oscillating power transmitting member movable radially to vary its radii reach in alternate strokes, in one to positively engage with said rolls and in the second releasable therefrom.

7. A device of the nature disclosed combining a pair of coacting paper feeding rolls, a lever oscillating member confined in its oscillating movement, and a member movably mounted on said oscillating member adapted to be moved radially thereon to engage with and transmit motion to said paper feeding rolls in one oscillating movement of the lever member, and releasable in a second movement.

8. A device of the nature disclosed combining a pair of coacting paper feeding rolls, a motion imparting member therefor comprising a crank lever, a guide plate pivoted upon said crank lever swinging therewith and confined in its arc of movement, and an arched plate slidable on said guide-plate yieldingly urged toward the crank of said lever and confined in its opposite movement whereby said crank in its rotation will forcibly move said arch plate into operative connection with one of said rolls to impart motion thereto during a continuous rotation of said lever with a reverse rotation releasing said parts.

9. A device of the nature disclosed com-

bining a pair of coacting paper feeding rolls, and means for rotating said rolls to deliver invariable constant lengths of paper comprising an oscillating motion impact member traversing in two planes, one to engage with the rolls and in the second releasable therefrom, a normalizing crank lever having a crank arm adapted to engage with said member and urge the same into driving connection with one of said rolls in an active lever movement to function said roll, means for partially interrupting a unison normalizing movement of said crank, and motion imparting member to displace this connection and release from the rolls.

10. In a mechanical movement, a support, an oscillating crank shaft journaled in said support and confined in its movements of oscillation, and a circular rack member oscillating with said crank shaft and capable of movement radially within confined limits, adapted to be engaged by the crank of said shaft to positively urge said member radially in one oscillating motion and permit recession thereof in the reverse motion.

11. In a mechanical movement, a driven member constant as to its direction of movement, a vibrating member, a motion transmitting member intervening said driven and vibrating members movable with said vibrating member, and thereby into operative connection with the driven member initially in one direction of movement and releasable therefrom in a second movement.

12. In a mechanical movement, a driven member constant as to its direction of movement, a vibrating member confined in its movements, a motion transmitting member intervening between said driven and vibrating members movable with said vibrating member, and thereby to and from said driven member at alternating intervals successive to each vibrating stroke.

13. In a mechanical movement, a driven member constant as to its direction of movement, a vibrating member confined in its movements, means for regulating its confining limits, a motion transmitting member intervening between said driven and vibrating members movable with said vibrating member, and thereby to and from said driven member at alternating intervals successive to each vibrating stroke.

14. In a mechanical movement, a driven member constant as to its direction of movement, a vibrating member confined in its movements, means for micrometrically regulating its confining limits, a motion transmitting member intervening between said driven and vibrating members movable with

said vibrating member, and thereby to and from said driven member at alternating intervals successive to each vibrating stroke, 65 and means for locking the vibrating member during the to and fro movement of said transmitting member.

15. In a mechanical movement, a rotative toothed member constant in its direction of rotation and definitely located, a vibrating member confined in its movement, a toothed member connecting with said vibrating member capable of being moved thereby into and out of toothed intermesh with said rotating member alternately upon each vibrating stroke and maintained in its relative position during the continuance of the vibrating stroke.

16. A device of the nature disclosed combining a pair of coacting paper feeding rolls rotatably mounted relatively in positive transmission connection, and an actuating member having a propelling contour operating in one line of travel during one stroke 85 to engage with and rotate said roll, and moving in a different line of travel on a return stroke.

17. In a device of the class described, a driven member, a two-part crank member 90 loosely mounted upon its axis, one element thereof movable radially upon the other within confined limits to vary the radii reach of said crank member and position the same into and out of an engaging plane 95 with said driven member, and means connected with the axis of said crank member for unitarily moving the parts with their axis and function the radial movement of said crank element.

18. In a device of the class described, a driven member, a swinging member radially extensible to vary its radii reach, and means for connecting with the axis of said swinging member for varying its reach into 105 engaging and disengaging planes with said driven member and swing said member.

19. In a device of the class described, a driven member, a member swinging within confined limits extensible to vary its radii 110 reach in alternate strokes in engaging and disengaging planes with said driven member, means for adjusting the confining limits to alter the stroke lengths of said swinging member, and means operative 115 through the axis of said swinging member for swinging and varying the reach of said last-named member.

In testimony whereof, I have hereunto set my hand.

ALBERT KRAUTH.
